(57) **CLAIM**

The ornamental design for a display screen or portion thereof with animated graphical user interface, as shown and described.

DESCRIPTION

FIG. 1 is a front view of the first image in a sequence for a display screen or portion thereof with animated graphical user interface, showing our new design;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof;

FIG. 7 is a front view of the seventh image thereof;

FIG. 8 is a front view of the eighth image thereof;

FIG. 9 is a front view of the ninth image thereof;

FIG. 10 is a front view of the tenth image thereof;

FIG. 11 is a front view of the eleventh image thereof;

FIG. 12 is a front view of the twelfth image thereof;

FIG. 13 is a front view of the thirteenth image thereof;

FIG. 14 is a front view of the fourteenth image thereof;

FIG. 15 is a front view of the fifteenth image thereof;

FIG. 16 is a front view of the sixteenth image thereof; and,

FIG. 17 is a front view of the seventeenth image thereof.

The double lined outer broken line showing of a display screen in all the figures and the broken line showing portions of the graphical user interface in FIGS. 14-17 are including for the purpose of showing portions of the article which form no part of the claim.

(Continued)

The dot-dash broken lines in the figures define the boundary of the claimed design and form no part thereof.

The appearance of the animated graphical user interface sequentially transitions between the images shown in FIGS. 1-17. The process or period in which one image transitions to another forms no part of the claimed design.
